UNITED STATES PATENT OFFICE.

FRANCIS WHITE AND HARRY WHITE, OF AKRON, OHIO.

MEANS FOR CONTROLLING PRIME MOVERS.

Application filed June 30, 1924. Serial No. 723,154.

This invention relates to methods and means for controlling prime movers particularly when employed for operating pumps, impellers or the like which are used to force liquid or gaseous fluids through a pipe system.

In the pumping or impelling of fluids as, for example, in the pumping of oil from wells or of water from wells, springs, or rivers, etc., into reservoirs, it is usually the case that an attendant cannot be employed to watch the operation of each of the great number of pumps which are ordinarily scattered over wide areas. Moreover, it frequently happens that for one reason or another a pump will cease to operate. This may result from binding of the pump shaft in the bearings or numerous other causes of every day occurrence.

20 The purpose of the present invention is to provide an improved procedure and apparatus whereby the destruction of pumping or impelling machinery including the prime mover itself will be prevented by automatically stopping the prime mover when the pump or other impeller fails to operate properly.

The chief object of the invention is to provide an apparatus for controlling the prime mover by the effect of less than normal air pressure on a control device caused by the surge of fluid backward through a pipe system when the pump or impeller fails to operate.

35 The above and lesser objects of the invention will become more apparent when the following specific description is read in connection with the accompanying drawings illustrating one embodiment of the invention 40 in an apparatus adapted to carry out the invention, it being understood that the same is not limited to the specific forms thereof shown and described.

Of the accompanying drawings:

45 Figure 1 is a side elevation showing the manner of applying the invention to an oil well pumping system; and

Figure 2 is a section on line 2—2 of Figure 1.

50 Referring to the drawings, 10 is a prime mover, in this case an electric motor, which is adapted to drive a shaft 11 extending vertically down into a well within a pipe 12, the shaft 11 being adapted to drive a pump (not shown) at the bottom of the well, which pump is arranged to force oil up the pipe

12. The shaft 11 extends upwardly through a coupling 13 on pipe 12 on which is mounted a bearing 14 for the shaft, the coupling 13 being adapted to deliver oil to a pipe 15 for conducting the same to a tank or the like (not shown).

In the pipe 15 is a gate valve 16 and a check valve 17, the latter being arranged to prevent flow of the oil backwardly into the well should the pump fail. Between the check valve 17 and the well, there is connected to the pipe 15, a smaller pipe 18 leading to a control device constructed according to the invention. The pipe 18 is connected to the control device by two pipes 19 and 20, pipe 19 having a gate valve 21 therein and pipe 20 having a check valve 22 therein, the latter being adapted to be held closed by the pressure of oil in the pipe 15 when the pump is properly working.

The control device in this instance, comprises a cylinder 23 in which is slidably mounted a piston 24 secured on a rod 25 which extends out of the cylinder and is connected by a cable 26 extending over pulleys 27 and 28 and connected to a trip lever 29 on an ordinary starting rheostat 30. The lever 29 is adapted to be disengaged from a latch 31 to permit suitable devices (not shown) to automatically break the circuit through leads 32 and 33 and the motor 10.

In operation, so long as the pump is operating normally, the check valve 17 will be open and check valve 22 will be closed. 90 Valve 21 may be left open sufficiently to keep piston 24 in the upper part of the cylinder 23, but preferably the valve 21 is opened only long enough to permit the cylinder to fill with oil, it then being closed and the oil being retained therein by pressure of the fluid in pipe 15 which, as stated before, keeps check valve 22 closed.

Should the pump fail for any reason, as, for example, because of binding of shaft 11 in bearing 14, the oil in pipe 15 will surge backwardly into the well, oil beyond the check valve 17 being prevented from running back into the well by closing of the valve. Closing of the valve 17 and the flow of oil not yet past the valve, out of pipe 15 back into the well will create a partial vacuum in the pipe 15 which will cause check valve 22 to open and will withdraw the oil from the cylinder 23, normal air pressure on the upper surface of piston 24 being such as to urge it downwardly whereby trip

lever 29 will release latch 31 and break the circuit to motor 10 to prevent the latter from burning out. After the trouble in the system is found and corrected, the rheostat control will be reset as will be understood.

While there is shown for purposes of illustration one form of prime mover it will be understood that the invention may be applied as well to the controlling of a valve in 10 a steam line leading to a steam engine or turbine, or for controlling a valve in a water line leading to a motor or turbine or to any other type of prime mover by the provision of suitable mechanism between the piston 24 15 or other vacuum controlled device and the prime mover control.

Modifications of the invention other than those disclosed herein may be resorted to without departing from the spirit thereof 20 or the scope of the appended claims.

What we claim is:

1. Apparatus of the class described, comprising a fluid conducting system, an impeller in the system, a prime mover for operating the impeller, and means connected to the system adapted to be actuated when the impeller fails to stop the prime mover, said means including a piston affected by normal air pressure on one side and by pressure in the system on the other, a check valve between the piston and the system normally held closed by pressure in the system, and a second valve between the piston and

the system adapted to be operated at will without affecting operation of said check 35 valve.

2. The combination with a well having a conduit for delivering liquid upwardly therefrom, said conduit being of such height as to back-drain by gravity against atmospheric pressure if the pump should fail, a pump for forcing a liquid out of the well through said conduit, a prime mover for driving the pump, and means for controlling the prime mover, of a check valve in said 40 conduit at the top of the well and a device connected to the conduit between the check valve and the well operable only by creation of a partial vacuum in the conduit by flow of the liquid from the conduit back into the 45 well, causing closure of the check valve, said device being connected to said controlling means to stop the prime mover.

3. The combination with a pipe system 55 adapted to back-drain by gravity against atmospheric pressure, an impeller for pumping a liquid through said system, and a prime mover for driving the impeller, of a check valve in the system adapted to be closed by a backward surge of the liquid in 60 the conduit, and means operable only upon closure of the check valve to stop the prime mover.
